**BLADE ASSEMBLY FOR EARTH
MOVING MACHINE**
William E. Harris, 3245 Park Ave., Paducah, Ky.
Filed Oct. 21, 1960, Ser. No. 64,044
7 Claims. (Cl. 37—144)

This invention relates to a novel construction of blade assembly and a novel means for attachment thereof to a prime mover or earth moving machine to enable the earth moving blade of the blade assembly to be raised or lowered, tilted and angularly adjusted relative to the prime mover to position the blade at a desired angle and depth relative to the prime mover and to the earth to be moved by the blade.

Another object of the invention is to provide a blade assembly including fluid pressure responsive means capable of being selectively operated from a point remote from the blade assembly to effect raising, lowering, tilting and angular adjustment of the blade.

Still a further object of the invention is to provide a blade assembly wherein the earth moving blade is equipped with a bottom digging or cutting edge capable of being angularly adjusted relative to the plane of the face of the blade.

Various other objects and advantages of the invention will hereinafter become more fully apparent from the following description of the drawings, illustrating a presently preferred embodiment thereof, and wherein:

FIGURE 1 is a top plan view, partly broken away, showing the blade mounting assembly in an applied position;

FIGURE 2 is a front elevational view, partly broken away thereof;

FIGURE 3 is a fragmentary side elevational view of the blade assembly looking from right to left of FIGURES 1 and 2;

FIGURE 4 is an enlarged fragmentary sectional view taken substantially along the line 4—4 of FIGURE 1;

FIGURE 5 is an enlarged vertical sectional view of a part of the unit, taken substantially along a plane as indicated by the line 5—5 of FIGURE 1;

FIGURE 6 is an enlarged fragmentary vertical sectional view taken substantially along a plane as indicated by the line 6—6 of FIGURE 1;

FIGURE 7 is a view primarily diagrammatic and partially in section showing one of the pressure responsive units of the blade assembly, and

FIGURE 8 is a view similar to FIGURE 7 of another pressure responsive unit.

Referring more specifically to the drawings, the blade assembly in its entirety and comprising the invention is designated generally 10 and includes an elongated rigid mounting member 11 which is disposed beyond an end of a prime mover, such as a tractor, with said member 11 preferably being disposed beyond a forward end 12 of such a prime mover and being supported thereby and rigidly secured thereto by two brace members 13 which are suitably fixed to or formed integral with the forward end 12 of the prime mover and with said mounting member 11. The mounting member 11 has a substantially flat vertical front side 14 which is provided with two grooves or channels 15 which open therethrough and through a top surface 16 and a bottom surface 17 of the mounting member 11. The grooves 15 are located near the ends of the member 11 and are of T-shaped cross section, as seen in FIGURE 1. The mounting member 11 is also provided at its ends with supporting arms or brackets 18 which are secured to its top surface 16 and which extend upwardly and forwardly therefrom beyond the front face 14, as seen in FIGURE 4.

The blade assembly 10 also includes an elongated blade

2

support 19 which has a vertically disposed rear wall 20, a bottom wall 21 and a top wall 22. A plurality of upright braces 23 are disposed internally of the blade support 19 and are secured to the walls 20, 21 and 22 thereof, to maintain the walls 21 and 22 substantially parallel to one another and at right angles to the rear wall 20. The blade support 19 is disposed in front of the mounting member 11 with the rear wall 20 spaced from and disposed substantially parallel to the front face 14.

10 A pair of elongated members of T-shaped cross section, designated generally 24 and 25, slidably engage in the grooves 15 for up and down sliding movement relative to the mounting member 11 and are engageable with and disengageable from said grooves only through the open 15 upper and lower ends thereof. Each of the members 24 and 25 has a restricted portion 26 which projects forwardly from the narrow outer or forward portion 27 of its groove 15. Each member 24 and 25 includes a stem or neck 28 of circular cross section which projects forwardly from a part of its restricted portion 26, as best seen in FIGURE 5, and an enlargement or head 29 at the outer end of the stem or neck 28 which is spaced from the portion 26. The stem 28 of the member 25 fits turnably in a circular opening 30 of the rear wall 20 and the face 25 stem 28 of the member 24 fits slidably and turnably in a horizontally elongated opening 31 of the wall 20. The openings 30 and 31 are disposed in alignment with one another, as seen in FIGURE 2. The heads 29 are disposed on the forward side of the wall 20 whereby the members 24 and 25 are attached to said wall 20 to form a part of the blade support 19. The heads 29 may be detachably connected to stems 28 or the stems 28 may be detachably mounted in the portions 26, as by means of threaded connections, or the heads 29 may be formed on the stems 28 after the stems have been engaged through the openings 30 and 31.

Bracket elements 32 are rigidly connected to and project outwardly from the lower ends of end flanges 23 and are disposed beyond the ends of the blade support 19 and adjacent its bottom wall 21. The closed end of a cylinder 33 of a fluid pressure responsive unit is pivotally connected by a fastening 34 to each bracket 32. The cylinders 33 of the two fluid pressure responsive units 35 and 36 extend upwardly from the brackets 32. Each unit 45 has a piston 37 slidably mounted in the cylinder 33 and a piston rod 37' which extends from said piston slidably through the other upper end of the cylinder. The upper ends of the piston rods 37' are pivotally connected by fastenings 38 to the forward ends of the arms 18, which 50 are located above the brackets 32. Each cylinder 33 has conduits 39 and 40 which communicate therewith and extend from end portions thereof, and each of which conduits is connected to a supply line 41 and a return line 42 by a conventional valve 43, as illustrated diagrammatically in FIGURE 7. The blade support 19 is supported on the mounting member 11 by the two fluid pressure responsive units 35 and 36, as will hereinafter be more fully described.

The blade assembly 10 also includes an earth moving 60 blade 44 which is elongated and preferably of a length greater than the length of the blade support 19. The blade 44 has rearwardly extending top and bottom walls 45 and 46, respectively. A rigid tube 47 extends between and is secured to the walls 45 and 46 in registration with 65 openings 48 thereof. The tube 47 is located midway of the ends of the walls 45 and 46 and remote from the blade 44. The walls are spaced apart a distance less than the spacing between the walls 21 and 22, and the portions thereof in which the openings 48 are formed, fit rotatably between said walls 21 and 22 with the openings 48 in alignment with externally flanged openings 49 of the walls 21 and 22. The openings 49 are

located midway of the ends of the walls 21 and 22 and remote from the rear wall 20. A pin 50 engages detachably through the openings 49 and 48 and the tube 47 for mounting the blade 44 for swinging movement about the axis of the pin 50 relative to the blade support 19 and the mounting member 11.

A second pair of fluid pressure responsive units 51 and 52 extend between the blade 44 and the rear wall 20 and are located between the bottom walls 21 and 46 and the top walls 22 and 45. The closed ends of the cylinders 53 of the units 51 and 52 are pivotally connected by fastenings 54 to the wall 20 and the outer ends of the piston rods 55 of said units 51 and 52 are pivotally connected by fastenings 56 to the blade 44. The units 51 and 52 are disposed on opposite sides of and spaced substantial distances from the pivot 50. The units 51 and 52 differ from the units 35 and 36, in that each cylinder 53 has only one conduit 57 which communicates therewith adjacent its closed end and which conduit is connected to a supply line 58 and a return line 59 by a conventional valve 60, as illustrated in FIGURE 8, for pressurizing the cylinder 53 to exert a force on the piston 61, contained therein, to move the piston rod 55 to an extended position.

The blade 44 includes a separate angularly adjustable bottom edge section 62 which extends substantially from end-to-end thereof and which includes a portion 63 of circular cross section and a blade portion 64 of triangular cross section which projects laterally outward from a part of the portion 63 and which extends to adjacent the ends thereof. The portion 63 is mounted to oscillate beneath the blade 44 by means of inwardly opening socket shaped end bearings 65, in which exposed ends of the portion 63 are journaled, and an intermediate bearing 66 which engages around the intermediate portion of the part 63 and through a notch 67 of the blade edge 64. The bearings 65 and 66 are secured as by fastenings 68 to the blade 44.

A fluid pressure responsive unit 69 includes a cylinder 70 which is swingably suspended by a bracket 71 from the top wall 45 for swinging movement toward and away from the blade 44, as best seen in FIGURE 4, and which has an extensible piston rod 72 extending from its lower end through a large opening 73 in the bottom wall 46. The lower end of the piston rod 72 is pivotally connected by a fastening 74 to a lever arm 74 which projects from the member 63 and which is disposed behind the blade edge 64. The pressure responsive unit 69 is identical with each of the units 35 and 36 and includes conduits 79 and 80, corresponding to the conduits 39 and 40, respectively, each of which is associated with a supply line and a return line and controlled by a valve, as illustrated in FIGURE 7.

To lower the blade support 19 and blade 44, relative to the mounting member 11, the valves 43 of the lines 40 are adjusted to position the diametrical bores 75 thereof in communication with the lines 40 and the supply lines 41, after which the valves 43, associated with the lines 39 of said units 35 and 36, are adjusted so that the radial bores 76 are in communication with the lines 39 and one end of the diametrical bores 75 is in communication with the return lines 42. Since the radial bore 76 connects with the diametrical bore 75, the fluid medium under pressure will flow from the cylinder 33 of each unit 35 and 36 through the line 39 and its valve 43 to the return line 42, allowing fluid under pressure to be supplied at the same time through the lines 40 to said cylinders 33 on the opposite sides of the pistons 37 for forcing the pistons 37 and rods 37' downwardly, to lower the blade support 19 and blade 44 relative to the mounting 11. When the parts have been lowered to a desired extent, the valves 43 of the lines 39 are turned slightly in a clockwise direction, as seen in FIGURE 7, to close said valves, after which the valves 43 of the lines 40 are turned slightly in a counterclockwise direc-

tion for closing said last mentioned valves. The valves are turned through arcs of less than 90° to closed positions. It will be understood that the members 24 and 25 slide in the channels 15 as the blade support 19 is lowered relative to the mounting member 11. Conversely, the blade support 19 and blade 44 can be raised relative to the mounting member 11 by positioning the bores 75 in alignment with the conduits 39 and supply lines 41 and thereafter positioning the bores 76 in communication with the lines 40 and so that the bores 75 of the valves 43 associated with the lines 40 will then communicate with the return lines 42.

If it is desired to tilt the blade support 19 and blade 44 about an axis disposed crosswise of said parts, one of the fluid pressure responsive units 35 or 36 can be actuated as previously described to either extend or retract the piston rod 37' thereof to lower or raise, respectively, the end of the blade support 19 connected thereto. In accomplishing this tilting operation, the member 24 or 25, located adjacent the fluid responsive member which is actuated, will slide in its groove 15, and the stem 28 of the member 24, through its turnable and slide engagement with the slot 31, will allow the wall 20 to pivot and slide relative to the member 24, while the opening 30 will allow the wall 20 to pivot relative to the stem 28 of the member 25. It will thus be seen that the units 35 and 36 allow the blade and blade support to be raised, lowered or tilted laterally of the prime mover in either direction.

In any position of adjustment of the blade support 19 relative to the mounting member 11, the blade 44 can be angularly adjusted relative to the blade support 19 about the pivot axis 50. This is accomplished by positioning the valve 60, as seen in FIGURE 8, of one of the units 51 or 52, in the position of FIGURE 8 with its diametrical bore 77 communicating with the conduit 57 and supply conduit 58. The valve of the other unit is then turned to a position 90° from that shown in FIGURE 8 in a counterclockwise direction, with its radial bore 78 communicating with the line 57 and one end of its diametrical bore 77 communicating with the return line 59, or corresponding to the position of the lower valve 43 of FIGURE 7. The cylinder 53 of the first mentioned unit will then be pressurized to extend the piston rod thereof, while pressure is being released from the cylinder 53 of the other unit, to swing the blade 44 about the pivot 50. For example, if the unit 51 is pressurized and extended, the blade 44 will swing counterclockwise as seen in FIGURE 1. The valves 60 are normally maintained in closed positions for maintaining a desired pressure on each of the units 51 and 52 to retain the blade 44 in a selected angularly adjusted position.

The pressure responsive unit 69 corresponds identically to the units 35 and 36, except that it is disposed in an inverted position and may be operated in the same manner as previously described in reference to the units 35 and 36, and as illustrated diagrammatically in FIGURE 7, for extending or retracting the piston rod 72 and for maintaining said piston rod in desired adjusted positions. FIGURE 4 shows the blade edge 64 in a normal operative position extending downwardly and forwardly for scraping and digging. To release the material which has been scraped and dug and which is being carried by the blade 44, pressure is supplied to the cylinder 70 through its lower conduit 79 and is released therefrom through the upper conduit 80 to retract the piston rod 72. This exerts an upward pull on the lever arm 74 for turning the blade section 62 counterclockwise, as seen in FIGURE 4. The blade section 62 is normally turned counterclockwise through an arc of about 60° from its position of FIGURE 4 so that the blade edge 64 will then be inclined downwardly and rearwardly rather than downwardly and forwardly, as shown, to what constitutes a dumping position to allow the earth to pass under the

blade edge 64. In this manner earth which has been previously dug or scraped and is being carried by the blade 44 can be released for filling a depression, where the blade is being utilized for leveling.

Various modifications and changes are contemplated and may be resorted to, without departing from the function or scope of the invention as hereinafter defined by the appended claims.

I claim as my invention:

1. A blade assembly for an earth moving machine comprising a mounting member adapted to be rigidly secured to and supported by a prime mover, said mounting member being disposed beyond an end of the prime mover and crosswise thereof, an elongated blade support disposed in front of said mounting member and longitudinally thereof, means connecting said blade support to the mounting member for vertical sliding movement of the blade support relative to the mounting member and for rocking movement of said blade support relative to the mounting member about horizontal axes disposed crosswise of the blade support and mounting member, an elongated earth moving blade, said blade support being disposed parallel to the blade and between said blade and the mounting member, means pivotally connecting the blade support to the mounting member for raising, lowering and tilting the blade support and blade relative to said mounting member, and means connected to the blade support and blade for angularly adjusting the blade relative to said blade support about the axis of said means pivotally connecting the blade to the blade support.

2. A blade assembly for an earth moving machine as in claim 1, said blade including a separate bottom edge section, means mounting said bottom edge section on the blade for turning movement of the bottom edge section relative to the blade about an axis disposed longitudinally of said blade and bottom section, and means connected to said blade and to the bottom edge section thereof for turning and angularly adjusting said bottom edge section relative to the plane of the blade.

3. A blade assembly for an earth moving machine as in claim 2, said last mentioned means comprising a fluid pressure responsive unit.

4. A blade assembly for an earth moving machine as in claim 1, said means connecting the blade support to the mounting member for raising, lowering and tilting the blade support and blade comprising fluid pressure responsive units connected to end portions of said blade support.

5. A blade assembly for an earth moving machine as in claim 1, said means connected to the blade support and blade for angularly adjusting the blade relative to the blade support comprising fluid pressure responsive units straddling the means pivotally connecting the blade to the blade support.

6. A blade assembly for an earth moving machine as in claim 1, said first mentioned means comprising forwardly opening slots of T-shaped cross section formed in said mounting member, two members of T-shaped cross section slidably engaging in said slots and having parts projecting forwardly therefrom and connected to longitudinally spaced portions of the blade support, one of said parts being swivelly connected to the blade support and the other of said parts being swivelly and slidably connected to the blade support for sliding movement of said last mentioned part longitudinally of the blade support.

7. A blade assembly for an earth moving machine comprising an elongated mounting member adapted to be rigidly connected to and disposed beyond an end and crosswise of a prime mover, an elongated earth moving blade spaced outwardly from and disposed substantially parallel to said mounting member, an elongated blade support disposed between the blade and mounting member and substantially parallel thereto, a pivot element pivotally connecting said blade to the blade support for swinging movement of the blade relative to the blade support about an axis disposed crosswise of the blade and blade support, connecting means connecting said blade support to the mounting member for up and down movement of the blade support and blade relative to the mounting member and for tilting movement of the blade support and blade relative to the mounting member about axes disposed at a right angle to the axis of said pivot element and crosswise of the mounting member and blade support, supporting means connecting the blade support to the mounting member for raising, lowering and tilting the blade support and blade relative to the mounting member, and extensible means connecting the blade support and blade for angularly adjusting the blade relative to the blade support about the axis of said pivot element.
